US00D524706S

(12) United States Design Patent (10) Patent No.: US D524,706 S
(45) Date of Patent: * Jul. 11, 2006

(54) BOAT CONSOLE

(75) Inventor: Alan Stinson, Gallatin, TN (US)

(73) Assignee: Stratos Boats, Inc., Murfreesboro, TN (US)

() Term: 14 Years

(21) Appl. No.: 29/185,672

(22) Filed: Jul. 1, 2003

(51) LOC (8) Cl. 12-16

(52) U.S. Cl. D12/192

(58) Field of Classification Search D12/192,
D12/317-318; 180/90; 280/750-752; 296/190.01,
296/191, 70; D10/46, 102, 98, 122-127;
114/255, 128

See application file for complete search history.
